UNITED STATES PATENT OFFICE

154,116

DESIGN FOR A DISPLAY BOX

Samuel H. Geffner, New York, N. Y.

Application November 28, 1947, Serial No. 142,839

Term of patent 3½ years

(Cl. D80—5)

To all whom it may concern:

Be it known that I, Samuel H. Geffner, a citizen of the United States of America, residing in New York, county of New York and State of New York, have invented a new, original, and ornamental Design for a Display Box, of which the following is a specification, reference being had to the accompanying drawing, forming part thereof.

Fig. 1 is a top plan view of a display box showing my new design.

Fig. 2 is an end elevational view thereof.

The sides of the box are conventionally plain. The essential feature of my design resides in the portions shown in solid lines.

I claim:

The ornamental design for a display box, substantially as shown and described.

SAMUEL H. GEFFNER.
